[57] ABSTRACT

A flip-flop circuit comprising a first inverter including

a first insulated gate field-effect transistor (MISFET), a second MISFET for storage and a third MISFET, the second MISFET being connected in series between the first and third MISFET's; a fourth MISFET for input and a fifth MISFET for control of writing as are connected in series between the first and third MISFET's; a second inverter including a MISFET for load and a sixth MISFET for storage as are connected in series with each other; a seventh MISFET for transfer as is connected between an output terminal of the first inverter and an input electrode of the sixth MISFET; and an eighth MISFET connected in parallel with the sixth MISFET. An output terminal of the second inverter is feedback-connected to an input electrode of the second MISFET, input electrodes of the third and seventh MISFET's are applied with a first train of clock pulses, an input electrode of the first MISFET is applied with a second train of clock pulses differing in phase from the first train of clock pulses, an input electrode of the fourth MISFET is applied with an input signal, input electrodes of the fifth and eighth MISFET's are applied with a writing control signal adapted to render the fifth and eighth MISFET's conductive at writing when at least the third and seventh MISFET's are conductive, and an output signal is derived from the input electrode of the sixth MISFET.

FLIP-FLOP CIRCUIT

BACKGROUND OF THE INVENTION

1. Field of the Invention

The present invention relates to a flip-flop circuit, and more particularly to a static flip-flop circuit composed of insulated gate field-effect transistors.

2. Description of the Prior Art

Flip-flop circuits composed of insulated gate field-effect transistors (hereinafter simply termed transistors) are broadly classified as dynamic flip-flop circuits and static flip-flop circuits. Since the dynamic flip-flop circuit is simple in construction, it is often employed in devices such as shift registers in which a number of flip-flop circuits are connected in cascade. In the case where the period for writing information into the flip-flop circuit is long, the static flip-flop circuit having a feedback path is more suitable.

Examples of typical static flip-flop circuits are shown in FIGS. 1 and 2. The static flip-flop circuit in FIG. 1 is constructed of a first inverter circuit composed of transistors Q₂₁ and Q₂₂, a second inverter circuit composed of transistors Q₂₃ and Q₂₄, a third inverter circuit composed of transistors Q₂₅ and Q₂₆, and transistors Q₂₇ - Q₂₉ which serve as transfer gates. The second inverter circuit and the third inverter circuit are connected in cascade. The output terminal of the third inverter circuit is feedback-connected through the transfer gate transistor Q₂₉ to the input terminal of the second inverter circuit, and information is statically retained by the feedback loop. The contents of the information to be retained by the feedback loop are determined by an input signal V_{in}, when the transfer gate transistor Q₂₇ is turned on by a writing control clock pulse $\phi_{1,r}$.

The gate electrodes of the transistors Q₂₈ and Q₂₉ are connected to receive clock pulses ϕ_2 , shown in FIG. 3(b), while the gate electrode of the transistor Q₂₇ receives the writing control clock pulses $\phi_{1,r}$, which differ in phase from the pulses ϕ_2 . The respective drain electrodes of the load transistors Q₂₁, Q₂₃ and Q₂₅ are connected to receive a negative DC voltage V_{DD}, and the respective gate electrodes are connected to a negative DC voltage V_{CC}, which is larger than the voltage V_{DD} by the threshold voltage V_{th} of the transistors, i.e., more than (|V_{CC}| = |V_{DD}| + |V_{th}|).

On account of the well-known substrate effect, the voltage to be applied to the gate electrodes of the transfer gate transistors Q₂₇ - Q₂₉ requires as high a level as the load transistors Q₂₁, Q₂₃ and Q₂₅ (for example, the same level as that of the voltage V_{GG}). The substrate effect arises for the reason that, in the case where the substrates of the respective transistors are commonly connected to a reference potential point (for example, in an integrated semiconductor circuit, the respective transistors have a single common semiconductor substrate), a voltage is impressed between the source electrode of each transistor and the substrate. The clock pulses ϕ_1 and ϕ_2 are therefore generated at high voltage levels outside the integrated semiconductor circuit device.

On the other hand, the writing control clock pulse $\phi_{1,r}$ is generated by taking, as shown in FIG. 3a, the logic result between the clock pulse ϕ_1 and a control signal X generated in, for example, an electronic computer. The logic result is established by a logic circuit consisting of transistors Q₃₁ - Q₃₅, the logic circuit

2

being similarly incorporated within the integrated semiconductor circuit in which the flip-flop circuit is constructed. Herein, the output potential of the logic circuit falls to an electric potential approximately equal to

5 the voltage V_{DD}. In general, accordingly, in order to raise the output potential, level conversion is performed by a circuit outside the integrated semiconductor circuit device to convert the output pulse to a clock control pulse of high level. It is also thought that, with 10 an identical integrated semiconductor circuit device, the output level of the logic circuit can be raised by additionally providing one power source. However, it is inevitable that the number of external terminals of the integrated circuit device must be increased with such 15 an arrangement, and therefore the specification of the integrated circuit device is subject to restriction.

When, in the static flip-flop circuit of FIG. 1, the load transistors Q₂₁, Q₂₃ and Q₂₅ are provided for clock drive in order to reduce power consumption, so-called 20 charge sharing arises. It is accordingly feared that an erroneous operation will occur.

On the other hand, with the static flip-flop circuit of FIG. 2, since the source electrodes of the transistors Q₇ and Q₈ for control of writing are grounded, the aforesaid substrate effect does not occur, and the voltage level of the writing control pulse $\phi_{1,r}$ may be low. Since the output terminal of an inverter circuit composed of transistors Q₂ and Q₄ is directly feedback-connected to the input terminal of an inverter circuit composed of 25 transistors Q₁ and Q₅ without the intervention of the transfer gate Q₂₉ of FIG. 1, the aforesaid charge sharing problem does not result, and the load transistors Q₁ and Q₂ can be clock-driven. As will now be explained, however, another problem arises with the circuit of FIG. 2.

35 The clock control pulse $\phi_{1,r}$ is formed by the logic circuit consisting of the transistors Q₃₁ - Q₃₅, which receives the clock pulse ϕ_1 and the control signal X as its input signals, as shown in FIG. 3a. In consequence, the 40 clock control pulse $\phi_{1,r}$ lags over the clock pulse ϕ_1 , as shown in FIG. 3b. Accordingly, the period of time during which the clock pulse ϕ_1 and the clock control pulse $\phi_{1,r}$ overlap, in other words, the period of time during which transistors Q₃ and Q₇ and transistors Q₃ and Q₈ are simultaneously rendered conductive for the 45 writing operation, is made shorter than the pulse width of the clock pulse ϕ_1 by the delay of the logic circuit, as illustrated by the hatched portion seen in FIG. 3b. The fact that the time interval of the concurrent conduction of the transistors is short, leads to the result 50 that the period of time for writing the input signal V_{in} into the flip-flop circuit is short. Unfortunately, this may cause an erroneous operation. For example, if the time interval of simultaneous conduction of the transistors Q₇ and Q₃ is short, the possibility of erroneous 55 operation due to the relationship between the discharge time constant of a circuit made up of the transistors Q₃, Q₄, Q₆ and Q₇, a voltage retained in the gate capacity of the transistor Q₄ and the threshold voltage V_{th} of the transistor Q₄ may result. If the simultaneous 60 conduction time of the transistors Q₈ and Q₃ is short, the possibility of an erroneous operation due to the relationship between the charge time constant of a circuit 65 consisting of the transistors Q₁, Q₃ and Q₄, the supply voltage V_{DD} and the threshold voltage V_{th} of the transistor Q₄, may occur. The latter case produces an especially different problem during charging. In order to

prolong the overlapping period of time between the clock pulse ϕ_1 and the clock control pulse $\phi_{1,r}$, the pulse width of the clock pulse ϕ_1 may be made sufficiently long. To this end, however, it is necessary to lower the clock frequency, which makes it inevitable that the speed of the shift register or the like must be lowered.

SUMMARY OF THE INVENTION

It is accordingly the principal object of the present invention to provide a flip-flop circuit which can utilize a writing control signal of low level and by which the period of time during which the writing control signal and a clock pulse overlap can be made equal to the full period of time of the clock pulse.

Another object of the present invention is to provide a flip-flop circuit which is miniaturized, in other words, the occupying area of which within an integrated semiconductor circuit is made small.

The other objects of the present invention will be apparent from the following detailed description when read in conjunction with the accompanying drawings.

BRIEF DESCRIPTION OF THE DRAWINGS

FIGS. 1 and 2 are schematic circuit diagrams of the prior-art static flip-flop circuits previously explained;

FIG. 3a is a schematic diagram of the logic circuit referred to in the previous description for producing the writing control signal $\phi_{1,r}$ of the clock pulse ϕ_1 and the control signal X;

FIG. 3b illustrates the clock pulses ϕ_1 and ϕ_2 , the control signal X and the writing control clock pulse $\phi_{1,r}$;

FIG. 4 is a schematic circuit diagram showing an embodiment of a static flip-flop circuit according to the present invention; and

FIG. 5 is a waveform diagram for explaining the operation of the circuit in FIG. 4.

DESCRIPTION OF THE PREFERRED EMBODIMENT

FIG. 4 shows an embodiment of the static flip-flop circuit according to the present invention. In the figure, the same parts as, or parts having the same functions as, the circuit of FIG. 2 are identified by common symbols. A capacitor C_1 corresponds to the junction capacities of a transistor Q_{11} and the transistor Q_6 and Q_5 and the capacities of connections for coupling these transistors to the transistor Q_3 . A capacitor C_2 corresponds to the gate capacities of the transistor Q_4 and a transistor Q_{18} and the connection capacities of the transistors Q_3 , Q_4 and Q_8 . The capacity of the capacitor C_1 is set at a value larger than the capacity of the capacitor C_2 . As the capacitor C_1 , a separate capacitor may be employed, connected between the drain electrode of the transistor Q_5 and ground.

One of the output electrodes of a transistor Q_{20} is connected to one of the output electrodes of each of the transistors Q_7 and Q_5 , while the other output electrode is grounded. The clock pulse ϕ_1 is applied to the gate electrode of the transistor Q_{20} , as well as to the gate electrode of the transfer gate transistor Q_3 . One of the output electrodes of a transistor Q_{17} and one of the output electrodes of the transistor Q_{18} are connected in common. The other output electrode of the transistor Q_{17} is connected to the DC voltage V_{DD} , while the other

output electrode of the transistor Q_{18} is grounded. The gate electrode of the transistor Q_{18} is connected to the gate electrode of the transistor Q_4 .

The clock pulse ϕ_2 is applied to the gate electrode of the transistor Q_{17} . Further, one of the output electrodes of a transistor Q_{19} is connected to the common connection point between the transistors Q_{17} and Q_{18} , an output signal V_{out} is provided from the other output electrode, and the clock pulse ϕ_2 is applied to its gate electrode, as well as to the aforesaid gate electrode of the transistor Q_{17} .

Unlike the flip-flop circuit in FIG. 2, the gate electrode of the transistor Q_{11} has the clock pulse ϕ_2 supplied thereto in the illustrated embodiment. A signal is used as the writing control signal X applied to the gate electrode of the transistor Q_7 which keeps the transistors Q_7 and Q_8 in the "on" state during the writing of information into the circuit during at least a time interval in which the transistors Q_3 and Q_{20} are in the "on" state.

The operation of the static flip-flop circuit according to the present invention will now be explained with reference to the waveform diagram of FIG. 5. In the figure, the upper level of each signal indicates the logic 1 (ground potential), while the lower level the logic 0 (negative potential). The writing control signal X employed herein is one which, similarly to the input signal V_{in} , is synchronized with the clock pulses ϕ_2 and has a pulse width equal to the period of the clock pulses ϕ_2 .

1. Before the clock pulse ϕ_1 becomes 0 to render the transistors Q_{20} and Q_3 conductive, the capacitor C_1 is previously charged during the 0 period of the clock pulse ϕ_2 . In the waveform diagram of FIG. 5, the capacitor C_1 is charged between times t_1 and t_1' .

2. When the writing control signal X becomes 0, both the transistors Q_7 and Q_8 become conductive. When the clock pulse ϕ_1 falls to 0 during this period, whether or not the charges stored in the capacitor C_1 or C_2 are discharged through the transistors Q_3 , Q_6 , Q_7 and Q_{20} is determined in dependence on only a new information signal V_{in} . This is because, upon conduction of the transistor Q_8 , the previous information having been stored in the transistor Q_5 is erased (because the transistor Q_5 becomes non-conductive). The result of the determination is stored in the capacitor C_2 .

Referring to FIG. 5, since the writing control signal X is 0 during the period $t_1 - t_3$, both the transistors Q_7 and Q_8 are conductive and the transistor Q_5 is non-conductive during the period. Since the transistors Q_3 and Q_{20} are conductive during the period $t_2 - t_2'$, the charges accumulated in the capacitor C_1 or C_2 are determined by the discharge irrespective of the previous information which has been stored in the transistor Q_5 and in dependence on whether the transistor Q_6 is rendered conductive or not (that is, by the input signal V_{in}).

Assuming that the input signal V_{in} is 1 during this period, as is illustrated in FIG. 5, the charges which have been previously accumulated in the capacitor C_1 , or the charges which have been accumulated in the capacitor C_2 before the time t_1 , are not discharged. Accordingly, either case occurs where the charges are left in the capacitor C_2 or where charges are supplied thereto from the capacitor C_1 . In either case, charges are present in the capacitor C_2 .

As illustrated in FIG. 5, the writing operation is similarly performed during a period from time t_3 to time t_{11} . During the period, however, the input signal V_{in} is 0, so that the charges which have been accumulated in the capacitors C_1 and C_2 are discharged through the transistors Q_3 , Q_6 , Q_7 and Q_{20} . In this way, the writing of the input signal V_{in} into the flip-flop circuit is completed.

3. On the other hand, when the writing control signal X becomes 1, both the transistors Q_7 and Q_8 become non-conductive. When the clock pulse ϕ_1 falls to 0 in the period, the charges accumulated in the capacitor C_1 or C_2 are determined as to whether they are discharged through the transistors Q_3 , Q_5 and Q_{20} , independently of the input signal V_{in} and by the previous old information in the transistor Q_5 , because the transistor Q_7 is non-conductive. The result is stored in the capacitor C_2 again.

Referring to FIG. 5, since the writing control signal X is 1 during the period of from time t_3 to time t_9 , the transistors Q_7 and Q_8 are non-conductive during the period. Since the transistors Q_3 and Q_{20} are conductive during the period $t_4 - t_4'$, the charges accumulated in the capacitor C_1 or C_2 are determined as to the discharge irrespective of the input signal V_{in} and in dependence on whether the transistor Q_5 is rendered conductive or not, that is, by the previous old information accumulated in the gate capacity of the transistor Q_5 . The information to be stored in the transistor Q_5 is determined by the information stored in the capacitor C_2 . It will be 1 if the information stored in the capacitor C_2 is 0, and it will be 0 if the same is 1. Therefore, since the information "0" has been perfectly stored in the capacitor C_2 at the time t_2' as in explanation (2) above, the information 1 is stored in the transistor Q_5 , and the charges which have been accumulated in the capacitors C_1 and C_2 are not discharged. In consequence, the charges are left in the capacitor C_2 as they are, and some charges having leaked therefrom in a period $t_2' - t_4$ are again supplied from the capacitor C_1 thereto. In other words, while the writing control signal X is 1, the information once stored in the transistors Q_3 and Q_5 are retained as they are.

4. During a period during which the clock pulse ϕ_2 is 0, an inverted signal corresponding to the information stored in the capacitor C_2 is derived as the output signal V_{out} from the transistor Q_{18} . For example, negative charges are accumulated in the capacitor C_2 during a period $t_3 - t_3'$, so that the transistor Q_{18} is conductive and the output signal V_{out} is at ground potential (logic 1). Similarly, the transistor Q_4 is non-conductive during a period $t_{11} - t_{11}'$, so that the output signal V_{out} is 0. In this manner, the reading operation is carried out.

The static flip-flop circuit according to the present invention as has thus far been described, has the following merits: 1. Since the pulse width of the clock pulse ϕ_1 can be exploited by 100 percent, the frequency of the clock pulses can be raised.

When the writing control signal X , as shown in FIG. 3b or FIG. 5, is used as the writing control pulse signal in the static flip-flop circuit of FIG. 2, the following erroneous operation arises. In the case where the writing control signal is 0, the transistor Q_8 is always rendered conductive during the reading operation (when the clock pulse ϕ_2 becomes 0), and the output signal V_{out} is always brought to ground potential independently of the input signal V_{in} . That is, since the output signal is

derived from the gate electrode of the transistor Q_5 , namely, from the output electrode of the transistor Q_8 which is conductive throughout the aforesaid period, such writing control signal X cannot be employed.

5. In contrast, with the static flip-flop circuit according to the present invention, as shown in FIG. 4, the output signal is derived from the gate electrode of the transistor Q_4 . Therefore, the gate voltage of the transistor Q_4 or the output signal V_{out} is not influenced by the control signal at all, and the aforesaid object of the present invention is accomplished. The writing control signal X may be such that it becomes 0 during the writing operation when at least the clock pulse ϕ_1 becomes 0.

2. As compared with the circuit in FIG. 1, the embodiment in FIG. 4 is larger by the three additional transistors employed. With the circuit of the present invention, however, the transistor Q_{11} for charging the capacitor C_1 and the series circuit member of the transistors Q_6 , Q_7 and Q_{20} , as well as the series circuit member of the transistors Q_5 and Q_{20} , the series circuit members forming under the specified conditions the conduction paths for discharging charges accumulated in the capacitor C_1 , are separately operated by the different clock pulses ϕ_1 and ϕ_2 , and hence, the necessity for considering the resistance ratio between both the constituents as in the prior art is eliminated. It is accordingly unnecessary to form the transistors Q_6 , Q_7 , Q_5 and Q_{20} at a larger area relative to the transistor Q_{11} . In substance, the circuit of the invention can be formed in an area smaller than that of the circuit in FIG. 2.

Transistors requiring large areas in consideration of the resistance ratios are the three transistors Q_4 , Q_8 and Q_{18} in the embodiment in FIG. 4, whereas the transistor having similar requirements in the circuit of FIG. 2 are the five transistors Q_6 , Q_5 , Q_7 , Q_4 and Q_8 .

Moreover, the transistors Q_6 and Q_7 in the prior-art circuit must have a resistance one-half as high as the transistors Q_4 and Q_8 in FIG. 1 and the transistors Q_4 , Q_8 and Q_{18} in FIG. 4, respectively. This means that there is a necessity for providing double areas. Ultimately, the ratio between the total areas of the five transistors in FIG. 1 and the three transistors in FIG. 4 becomes 6 : 3 = 2 : 1.

45. Although, in the embodiment of the present invention, the transistors Q_2 and Q_{17} are employed as the loads of the respective transistors Q_4 and Q_{18} , they may be replaced with usual impedance elements, such as resistors, or with devices having similar performances. It is also possible to drive the transistors Q_4 and Q_{18} with a DC voltage. Although, in the embodiment, the input signal V_{in} is supplied to the transistor Q_6 , it may of course be made to feed the input signal V_{in} to the transistor Q_7 and to apply the signal X for the writing control of the input signal V_{in} to the transistor Q_6 .

With the embodiment, a set preference (RSS) flip-flop circuit can be constructed in such a way that the output electrodes of another transistor Q_{16} (not shown) are interposed between one of the output electrodes of the transistor Q_8 and ground, and that a reset signal is supplied to the gate electrode of the transistor Q_{16} , while a set signal is supplied to the gate electrode of the transistor Q_6 .

60. Although, in the described embodiment, the MOS field-effect type transistor is employed, it is a matter of course that they are not restricted thereto insofar as the MIS field-effect type may also be utilized.

As stated above, in accordance with the flip-flop circuit of the present invention, such various advantages are brought about that the pulse width of the clock pulse ϕ_1 can be effectively exploited by 100 percent and that its occupying area in an integrated circuit can be made small.

What is claimed is:

1. A flip-flop circuit comprising a voltage source, a first inverter circuit including a first impedance element and first and second insulated gate field-effect transistors connected in series across said voltage source, third and fourth insulated gate field-effect transistors connected in series across said first insulated gate field-effect transistor, a second inverter circuit including a second impedance element in series with a fifth insulated gate field-effect transistor across said voltage source, a sixth insulated gate field-effect transistor connected between an output terminal of said first inverter circuit and the input electrode of said fifth insulated gate field-effect transistor, a seventh insulated gate field-effect transistor connected in parallel with said fifth insulated gate field-effect transistor and having its input electrode connected to the input electrode of one of said third and fourth insulated gate field-effect transistors, and output means for deriving an output signal from the input electrode of said fifth insulated gate field-effect transistor, the output terminal of said second inverter circuit being feedback connected to the input electrode of said first insulated gate field-effect transistor.

2. A flip-flop circuit as defined in claim 1 wherein said first and second impedance elements consist of eighth and ninth insulated gate field-effect transistors.

3. A flip-flop circuit as defined in claim 2 further including gating means for applying first gating signals to the input electrode of said second insulated gate field-effect transistor and second gating signals to the input electrodes of said eighth and ninth insulated gate field-effect transistors.

4. A flip-flop circuit as defined in claim 3 wherein said gating means is connected to the input electrode of said sixth insulated gate field-effect transistor to apply first gating signals thereto.

5. A flip-flop circuit as defined in claim 1 wherein said output means includes a third inverter circuit comprising a tenth insulated gate field-effect transistor connected in series with a third impedance element across said voltage source, the input electrodes of said fifth and tenth insulated gate field-effect transistors being interconnected.

6. A flip-flop circuit as defined in claim 5 wherein said first and second impedance elements consist of eighth and ninth insulated gate field-effect transistors.

7. A flip-flop circuit as defined in claim 6 further including gating means for applying first gating signals to the input electrode of said second insulated gate field-effect transistor and second gating signals to the input electrodes of said eighth and ninth insulated gate field-effect transistors.

8. A flip-flop circuit as defined in claim 7 wherein said third impedance element is an eleventh insulated gate field-effect transistor having its input electrode connected to said gating means to receive said second gating signals.
